(57) **CLAIM**

The ornamental design for a camera as shown and described.

DESCRIPTION

FIG. 1 is a back, top, left perspective view of a first embodiment of a camera showing my new design;

FIG. 2 is a top, left perspective view;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is top plan view thereof;

FIG. 8 is a bottom plan view thereof;

FIG. 9 is an enlarged cross-sectional perspective view thereof cut along the lines 9-9 and 9'-9' of FIG. 1; and,

FIG. 10 is an enlarged cross-sectional perspective view thereof cut along the lines 10-10 and 10'-10' of FIG. 2.

The broken lines illustrating portions of the camera form no part of the claimed design. Dot-dash broken lines defining the boundaries of the claimed design form no part of the claimed design. Dot-dot-dash broken lines defining the boundaries of the cross-sectional view form no part of the claimed design.

1 Claim, 10 Drawing Sheets
